UNITED STATES PATENT OFFICE

113,893

DESIGN FOR A BRASSIÈRE BODICE

Ruth Freedman, New York, N. Y.

Application April 30, 1937, Serial No. 69,084

Term of patent 7 years

To all whom it may concern:

Be it known that I, Ruth Freedman, a citizen of the United States, residing at the Borough of Bronx, city of New York, in the county of Bronx and State of New York, have invented a new, original, and ornamental Design for a Brassière Bodice, of which the following is a specification, reference being had to the accompanying drawing, forming part thereof.

In this invention for a brassière bodice, Fig. 1 shows a front view thereof and Fig. 2 indicates a rear view of Fig. 1.

I claim:

The ornamental design for a brassière bodice, as shown.

RUTH FREEDMAN.
